DISPENSING CONTAINER

Joseph Henry Percy, New York, N. Y., assignor
to Colgate-Palmolive-Peet Company, Jersey
City, N. J., a corporation of Delaware

Application January 1, 1942, Serial No. 425,285

9 Claims. (Cl. 222—455)

The present invention relates to containers and, more particularly, to cartons of cardboard, pasteboard and the like adapted for uniform delivery of a measured portion of the content.

Cardboard and paper boxes and cartons have been used for many years for packaging various materials intended for household use. Such containers have been found to be well suited for packaging products in the form of powders, grains, beads, flakes, chips, short rods, tubes, etc. Cardboard and pasteboard cartons and boxes are employed by packagers of detergents, both soap products and synthetic detergents; food products, including cereals, processed grains, sugar, dried fruits and vegetables, and prepared flours; salts; baking soda; washing soda; powdered wax, and other materials in comparatively finely divided form. Many of these packages are provided with scored or perforated sections and/or pouring spouts adapted for improved dispensing of the contents, and many are also provided with instructions to the consumer as to the amount of the content to be used for various purposes. However, so far as is known, no means has ever been provided in such cartons for regulating or measuring out the amount of the delivery.

It is an object of the present invention to provide a container of novel and improved construction for regulated delivery of the contents thereof.

It is also an object of this invention to provide a novel carton adapted to deliver a substantially uniform quantity of its contents at a single inversion.

It is another object of the invention to provide a novel carton having means integral therewith for regulating the maximum amount of contents which can be continuously delivered from the carton.

A further object of the invention is to provide a novel unitary blank so constructed as to be readily and economically formed into a carton adapted for regulating the delivery of the contents thereof.

Other objects and advantages of the present invention will be apparent from the following description, taken in conjunction with the accompanying drawings, in which:

Fig. 1 depicts a plan view of a carton blank made in accordance with the present invention;

Fig. 2 illustrates a perspective view of a tubular carton during its formation from this carton blank;

Fig. 3 is a plan view of a blank for another mod-

ification of the novel carton of the present invention;

Fig. 4 shows a perspective view of a completed carton formed from the blank of Fig. 3, with part broken away for greater clarity;

Fig. 5 represents a longitudinal sectional view of the carton of Fig. 4 during the initial inversion of the carton;

Fig. 6 illustrates a view similar to Fig. 5 during the return of the carton to an upright position;

Fig. 7 depicts a similar longitudinal section, showing a subsequent inversion of the carton and delivery of a regulated amount therefrom; and

Fig. 8 is a longitudinal section of said carton after its return to an upright position and ready for further delivery of its contents.

The carton according to the present invention is, in its preferred embodiment, of the tubular type and comprises in integral form front and back face sections and side sections, with flaps and tabs dependent from said sections folded across the ends in overlapping relation to seal the same. Within the carton, adjacent one side section, there is a baffle partition extending from the front to the back section for almost the entire height of the carton to form a delivery passage along the side of the carton. The partition is preferably relatively close to and substantially parallel to the side section and is spaced from one end of the carton to form a turn connecting the delivery passage with the main body of the carton. The carton is adapted to be opened, perforated or punctured at a part of the delivery passage non-contiguous to this turn and preferably near the opposite end of the carton whereby a dispensing port is provided. For even more uniform delivery, a plurality of baffle partitions can be provided adjacent one of the side sections, said partitions being coextensive in width with and preferably parallel to said side section and being alternately spaced from the ends of the carton to form a single series-connected serpentine delivery passage.

In providing a blank for the carton structure, it is preferred that the partition baffles be integral with the walls of the carton and that they be separated therefrom and from each other by connecting strips adapted to be adhesively affixed to the inside of the carton walls.

The invention will now be more fully described with respect to particular embodiments thereof. Reference may be had to the accompanying drawings wherein like characters denote similar parts in the respective figures.

Referring to Figs. 1 and 2, wherein a modifi-

cation of the present invention is depicted, the novel carton blank comprises two large rectangular face sections 1 and 2, alternatively the front and back of the carton. These sections are connected by an intermediate rectangular section 3 which forms a side of the carton, fold lines 4 and 5 being provided between sections 1—3 and 2—3, respectively. A rectangular section 6 similar to section 3 is connected to face section 2 at the side of the face section opposite section 3, fold line 7 being provided between sections 2 and 6.

A baffle partition 8 is integrally joined to side section 6 by means of a connecting strip 9, fold lines 10 and 11, respectively, being provided between section 6 and the connecting strip and between the connecting strip and the baffle partition. The baffle partition is of substantially the same width as the side sections but is shorter in length, being cut out or indented at the bottom end thereof to any desired extent. The connecting strip 9 is coextensive in length with side section 6 along fold line 10 and is of desired width, said connecting strip being adapted for adhesive attachment to face section 1. The amount of material which can be delivered from the carton at a single inversion is largely determined by the width of the connecting strip, which determines the width of the delivery passage, and by the amount of indentation of the partition, which is a controlling factor in determining the amount of contents which can flow from the main body of the carton into the delivery passage. At the side of partition 8 opposite connecting strip 9, there is a tongue 12, fold line 13 being provided at the juncture of the tongue with the partition, said tongue is adapted to be adhesively affixed to face section 2.

Rectangular flaps 21 and 22 are respectively attached to the top and bottom ends of face section 1, and rectangular flaps 23 and 24 are similarly attached to face section 2. Fold lines 25, 26, 27 and 28 are respectively provided at the juncture of these flaps with the respective side sections. Similarly, tabs 29, 30, 31 and 32 are attached to the tops and bottoms, respectively, of side sections 3 and 6, respectively, and fold lines 33, 34, 35 and 36 are provided at the respective junctures of these tabs with said side sections. The flaps and tabs are substantially coextensive with the respective top and bottom edges of the sections to which they are attached. Scored lines 41, 42 and 43 are provided upon flaps 21 and 23 and tab 31, respectively, and said scored lines are so located as to be in cooperating position with each other and above the delivery passage when the carton is formed and sealed. The dispensing port adapted to be formed thereby should not extend beyond the area of the top of the delivery passage.

In forming a carton from this blank, connecting strip 9 is folded inwardly at right angles to section 6 along line 10, and partition 8 is folded inwardly along line 11 at right angles to connecting strip 9. Tongue 12 is preferably folded backward along line 13 at right angles to the partition, although it may alternatively be folded inwardly. Section 6 is then folded inwardly along line 7 at right angles to section 2. One face of tongue 12 thus lies along the back of section 2, and the tongue is firmly glued to section 2 along this face to fix the position of the partition within the carton. Side section 3 is then folded inwardly at right angles to face sec-

tion 2, and face section 1 is similarly folded inwardly at right angles to side section 3. Section 1 is preferably firmly glued upon the connecting strip 9, whereby a tube having a partition near one side thereof is formed. Flaps 22 and 24 and tabs 30 and 32 are brought to a horizontal and overlapping position, being folded along lines 25, 28, 34 and 36, respectively, to form a bottom for the carton. The overlapping flaps and tabs are firmly glued together, each upon the surface beneath it, the presence of a form within the carton for permitting sufficient pressure to be applied to provide a good seal being desirable. It is also preferred that the glue or other suitable adhesive material be permitted to dry before the carton is filled with the material to be contained therein.

With the bottom and sides of the carton firmly sealed and the top open to receive its ultimate content, the main body of the carton is filled. A portion of the contents flows into the bottom part of the delivery passage through the turn at the bottom of the partition 8, the proportion of the content being in part controlled by the area of the turn and the width of the delivery passage. Tabs 29 and 31 and flaps 21 and 23 are folded down into a horizontal position along their respective fold lines in overlapping position. The flaps and tabs are adhesively affixed to each other to seal the top of the carton, and the scored lines 41, 42 and 43 are in cooperating position above the delivery passage.

When it is desired to dispense material from the carton, the top of the carton is punctured along the scored lines to provide a dispensing port. The carton is then inverted, and such portion of its content as is in the delivery passage is poured through this port. The remainder of the content of the carton flows to the top of the main body of the carton and is prevented from reaching the dispensing port by the partition. Upon returning the carton to its upright position, a further portion of the contents flows into the delivery passage through the turn at the bottom of the partition, and the carton is ready to deliver a further quantity. In this modification, especially with finely comminuted materials, there is a tendency for the material in the delivery passage to rise to the level of the material in the main body of the carton. For this reason, although the amount of material delivered at a single rapid inversion is limited and has for a maximum the volume of the delivery passage, the quantity dispensed at successive inversions may not be exactly uniform but may tend to decrease as the content of the entire carton is diminished with use.

An improved modification of the present invention is illustrated at Figs. 3 to 8. In this modification, a second baffle partition is provided for obtaining greater uniformity in the quantity of material dispensed at each inversion. A carton blank adapted for forming a tubular carton and having face and side sections and top and bottom flaps and tabs, as in the modification described supra, is provided. At the side of section 6 opposite face section 2, there is a baffle partition 8 connected to section 6 by a connecting strip 9, fold lines 10 and 11 being provided between section 6 and the connecting strip and between the connecting strip and partition 8, respectively. At the other side of the partition there is a second connecting strip 12, and a fold line 13 at the juncture therewith of partition 8 is provided. A second partition 14

is attached to the second connecting strip along fold line 15, and a tongue 16 is attached to the second partition at the opposite side thereof along fold line 17. Connecting strip 9 and tongue 16 are adapted to be adhesively affixed to face section 1, and connecting strip 12 is similarly adapted for adhesive attachment to face section 2.

Each of the two partitions is of substantially the same width as the side sections, and the widths of the connecting strips are as desired, depending upon the required width of the respective arms of the delivery passage to be formed. The first or outer baffle partition 8 is cut out or indented at the bottom thereof to provide a turn 8a between the two arms of the delivery passage, and the second or inner baffle partition 14 is similarly indented at the top end thereof to form a turn 14a between the delivery passage and the main body of the carton. It will be appreciated from the foregoing that the respective indentations in the two partitions may be of the same or of different size and shape and that the connecting strips 9 and 12 may be of the same or different widths to provide arms of the delivery passage in such volume as is desired. At the top of side section 6, a scored line 44 is provided which is adapted for puncture to provide a dispensing port 45.

In forming a carton from this blank, connecting strip 9 is folded at right angles to section 6 along fold line 10, and partition 8 is similarly folded inwardly along line 11 at right angles to connecting strip 9. In similar manner, connecting strip 12 and partition 14 are folded backwards at right angles along lines 13 and 15, respectively, a tongue 16 is folded preferably forwardly along line 17 at right angles to partition 14, although the tongue may alternatively be folded backwards. Section 6 is then folded inwardly at right angles to section 2, bringing connecting strip 12 into contact with the inside of face section 2, where it is firmly glued. Section 3 is then folded inwardly at right angles along line 5, and section 1 is similarly folded inwardly at right angles to section 3 along line 4. The inside of section 1 is then firmly glued upon connecting strip 9 and tongue 16, thereby forming a tube having two partitions therewithin in fixed position with respect to the walls of the carton.

In this manner, a carton having a main body 37 and a delivery passage connecting therewith through turn 14a at the top of the carton can be provided. The delivery passage has two arms, an inner arm 38, which connects with the main body 37 of the carton directly through the turn 14a at the top thereof, and an outer arm 39, which connects with the inner arm of the delivery passage through the turn 8a at the bottom of the carton. The bottom tabs and flaps are folded horizontally upon each other in overlapping position and glued together as aforesaid, and the main body of the carton is then filled with its ultimate content. The tabs and flaps at the top are then also sealed down, as described supra, and the carton is ready for delivery to the consumer, as shown at Fig. 4.

Referring now to Figs. 5 to 8, which represent longitudinal sectional views of this modification, Fig. 5 indicates the position of the contents upon the initial tipping or inversion of the carton. A portion of the contents of the main body 37 flows through turn 14a into the inner arm 38 of the delivery passage and remains at the top portion

of this arm for the short interval of time during which the carton is inverted. As the carton is returned toward its upright position (see Fig. 6), the material in the inner arm drops to the bottom of said inner arm and flows through turn 8a into the outer arm 39 of the delivery passage, the remainder of the contents falling back to the bottom of the main body of the carton. Upon the next and subsequent inversions (see Fig. 7), the portion at the bottom of the outer arm of the delivery passage pours through the dispensing port 45 while an additional portion from the main body of the carton flows through turn 14a into the inner arm 38 of the delivery passage. Upon returning the carton to its original upright position (see Fig. 8), this portion flows down the inner arm of the delivery passage and partly through the turn 8a into the outer arm, ready to be dispensed at the next inversion of the carton.

Due to the fact that the inner partition 14 is cut out or indented at its top and that there is, therefore, no connection between the main body of the carton and the delivery passage at the bottom of the carton in this modification, there is no opportunity for the contents to sift into the delivery passage while the carton is in the upright position. For this reason, each inversion of the carton transfers a substantially uniform quantity of material from the main body of the carton into the delivery passage, and the amount of the contents dispensed at each inversion is therefore substantially constant while there is still material in the carton. The amount of the contents dispensed at each inversion can be regulated by providing suitable heights and widths of the turns 8a and 14a in the partitions and by providing any desired width for arms of the delivery passage. It will be appreciated from the foregoing that more than two partitions can be provided, if desired, with even greater uniformity of delivery, the indentations of said partitions being alternatively at the lower and the upper portions of the carton.

The partitions provided, though preferably parallel to the sides of the cartons, may be oblique thereto and to each other or may even be between adjoining walls, that is, across a corner. The partitions may be inserted, either together or separately, rather than folded from the same blank as the walls of the carton, and the size and shape of the indentation or cut-off may be varied as desired. Although it is preferred to provide indentations, recesses or cutoffs at the ends of the partitions, any connections or turns formed by other means for cutting out an aperture in the end portion of the partition are satisfactory. The carton may be of any type, tubular or non-tubular, and may be of wood, metal, plastic or any other material instead of cardboard and pasteboard, and the partitions may be of the same or of different material from the walls of the carton.

Because of the generally regular shapes of the blanks depicted in the drawings, it has been found expedient to show the tabs of the carton of the invention as being square in shape. Although it is desired to employ tabs of substantially the same dimension as the width of the side of the carton for greater effectiveness, such elements may be of any convenient length or shape in their other dimension. Similarly, flaps are preferably coextensive with the sections from which they are dependent but may vary as desired, in size and/or shape, in their other dimension.

While the present specification has described the novel carton with respect to a particular

position for holding the same, it will be appreciated that printing and labels may be so applied to the outer surface thereof that the ultimate consumer will be induced normally to hold the carton in a manner and position other than that in which it will ordinarily have been filled. Thus, while it is preferred to introduce the contents through the top end of the cartons, as set forth supra, it may alternatively be filled through the bottom and/or intelligence may be printed upon the carton upside down or in any other desired position. Similarly, although the various surfaces of the carton have been designated as faces, sides and ends, such designation refers in general to the customary manner of holding the carton. Likewise, while the construction of the carton from the blank has been described with reference to a particular order of folding operations, those skilled in the art will appreciate from the foregoing that such order is merely illustrative and that any suitable order may be employed.

While it is generally preferred to fix the partitions in place by securing the connecting strips to the walls of the cartons, as well as the tongues to the carton walls, as by adhesive, stapling, stitching or the like, a satisfactory seal for some purposes, especially where the contents is less finely comminuted, can be obtained by attaching only the tongue. It will be appreciated from the foregoing that, in either of these modifications, the carton tubes can be assembled and partitions substantially parallel to a carton wall can be put in place by the manufacturer before shipment to the packager in flat, knockdown condition with flaps and tabs unsealed. The partitions, though preferably lying parallel to the face and side sections in the carton blank and being joined thereto by the connecting strips, may be attached directly to any of said sections or may be integral with the blank at any other edge thereof. Thus, the face and side sections of the blank, which are preferably serially joined, as shown in Figs. 1 and 3, may be separated either between sections or vertically across a single section by one or more partitions attached to said sections either directly or by connecting strips or tongues. Moreover, a face or side section of the blank at a vertical edge or vertically across a section may be directly connected to a partition, which in turn is connected to a strip for attaching to another section. Additional partitions and connecting strips may be serially connected to this strip for forming a plurality of delivery passage arms. In this modification, the other end of the blank may preferably be a tongue for attaching to the partition or section. The partitions may also be attached to tabs or flaps dependent from said sections, or from a bottom section where such is employed.

Although the present invention has been described with respect to particular embodiments and particular constructive features, it will be appreciated that equivalent elements can be used and that variations and modifications of the invention can be made without departing from the spirit thereof. Thus, the container of the invention may be employed as a holder for an inner carton fitting into the main body of said container and having a dispensing orifice adjacent the turn between the main body and the delivery passage. For example, a container of molded plastic or metal may be provided with partitions, delivery passage and dispensing port, as aforesaid, and with a tight-fitting cover and may be adapted to contain in its main body por-

tion a pasteboard or cardboard carton of suitable size and having a scored section adapted to be opened by the ultimate consumer and to be placed adjacent the turn into the delivery passage of the container. This and other variations and modifications are believed to be within the scope of the present specification and within the purview of the appended claims.

I claim:

10. 1. As a new article of manufacture, a container having faces, sides and ends, each end comprising flaps extending from both faces and tabs extending from both sides coextensive in width with said faces and said sides respectively, and at least two partitions therewithin extending from one face to the opposite face for substantially the full length of said faces and adjacent one side, said partitions and said adjacent side defining a delivery passage and said partitions being cut out adjacent alternate ends of the container to form turns therein, and said container being adapted for dispensing material from an arm of said delivery passage defined by said adjacent side and the partition nearest said side.
15. 2. As a new article of manufacture, a container having faces, sides and ends, each end comprising substantially rectangular flaps extending from both faces and substantially rectangular tabs extending from both sides coextensive in width with said faces and said sides respectively, and at least two partitions therewithin extending from one face to the opposite face for substantially the full length of said faces and adjacent one side to form a main body and a delivery passage having at least two arms, said partitions being cut out adjacent alternate ends of the container to form turns therein, and the outer arm of the delivery passage being adapted for dispensing material from said container at a point therein remote from the turn in the partition nearest said adjacent side.
20. 3. As a new article of manufacture, a carton having faces, sides and ends, each end comprising substantially rectangular flaps extending from both faces and substantially rectangular tabs extending from both sides coextensive in width with said faces and said sides respectively, and at least two partitions therewithin extending from one face to the opposite face for substantially the full length of said faces and adjacent one side to form a main body and a delivery passage having at least two arms, said partitions being alternately spaced from the ends of the carton to form turns, and said adjacent side being adapted for forming a port remote from the turn in the partition nearest said side.
25. 4. As a new article of manufacture, a carton having faces, sides and ends, each end comprising substantially rectangular flaps extending from both faces and substantially rectangular tabs extending from both sides coextensive in width with said faces and said sides respectively, and at least two partitions therewithin extending from one face to the opposite face for substantially the full length of said faces and adjacent one side to form a main body and a delivery passage having at least two arms, said partitions being alternately spaced from the ends of the carton to form turns, and said adjacent side being adapted for forming a port adjacent the end of the carton opposite the end from which the partition nearest said side is spaced.
30. 5. As a new article of manufacture, a unitary carton blank having face and side sections, a flap

at each end of each face section and a tab at each end of each side section, said flaps and tabs being coextensive in width with said face sections and said side sections respectively and being in foldable relation to said sections, at least two partitions of length and width respectively substantially equal to the length and width of a side section and cut out adjacent top and bottom ends alternately of said partitions, and connecting strips between said sections and said partitions and between the several partitions whereby a tubular carton with a delivery passage having at least two arms defined by said partitions and a side section can be formed.

6. As a new article of manufacture, a unitary carton blank having face and side sections, a substantially rectangular flap at each end of each face section and a substantially rectangular tab at each end of each side section, said flaps and tabs being coextensive in width with said face sections and said side sections, respectively and being in foldable relation to said sections, a first partition of length and width respectively substantially equal to the length and width of a side section and indented at the bottom of said partition, a first connecting strip intermediate said partition and said sections, a second partition of length and width respectively substantially equal to the length and width of a side section and indented at the top of said second partition, and a second connecting strip intermediate the first and second partitions whereby a tubular carton with a delivery passage having two arms defined by said partitions and a side section can be formed.

7. As a new article of manufacture, a unitary carton blank having face and side sections, a substantially rectangular flap at each end of each face section and a substantially rectangular tab at each end of each side section, said flaps and tabs being coextensive in width with said face sections and said side sections respectively and being in foldable relation to said sections, a first partition of length and width respectively substantially equal to the length and width of

a side section and indented at the bottom of said partition, a first connecting strip intermediate said partition and said sections, a second partition of length and width respectively substantially equal to the length and width of a side section and indented at the top of said second partition, and a second connecting strip intermediate the first and second partitions whereby a tubular carton with a delivery passage having two arms

10 formed by said partitions and a side section is provided, said side section being scored at the top thereof to provide a puncturable portion in the delivery passage.

8. A dispensing package comprising a rectangular box having side and end walls, and provided near one corner with a discharge opening, and measuring means contained within the box adjacent the corner having said opening, said means including a pair of spaced partition walls 15 secured to one of two opposite side walls of the box and extending between said side walls parallel with the other two side walls and with each other, the partition nearest said opening being imperforate and extending substantially to the 20 end wall of the box adjoining said measuring means, and the other partition having its edge spaced from said end wall to provide a passageway therebetween.

9. As an article of manufacture, a folded blank 25 box of the tubular type, in flat or collapsed condition, and having side and edge walls, said collapsed box having housed within it a measuring cell comprising hingedly connected side and end walls, said cell being also in collapsed condition, 30 with its side walls superposed, and means anchoring said cell to said box walls in such position that said superposed side walls overlie the fold line between one of the side walls of the box and the adjacent edge wall thereof, whereby, when said 35 box is opened up into tubular form, said cell is also opened up into similar tubular form with the side walls thereof parallel with and spaced from the adjacent edge wall of the box.
